US0D1002077S

(12) **United States Design Patent** (10) **Patent No.:** **US D1,002,077 S**
(45) **Date of Patent:** **** Oct. 17, 2023**

(54) **PROJECTION LAMP**

(71) Applicant: **Anhui Guangju Bozhong electronic technology Co., LTD**, Wuhu (CN)

(72) Inventors: **Ziqiang Sun**, Wuhu (CN); **Yuan Chang**, Wuhu (CN)

(73) Assignee: **Anhui Guangju Bozhong electronic technology Co., LTD**

(**) Term: **15 Years**

(21) Appl. No.: **29/896,506**

(22) Filed: **Jul. 5, 2023**

(30) **Foreign Application Priority Data**

Jun. 8, 2023 (CN) 202330352635.8

(57) **CLAIM**

The ornamental design for a projection lamp, as shown and described.

DESCRIPTION

FIG. 1 is a first perspective view of a projection lamp showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the projection lamp thereof. The broken lines shown in the drawings depict portions of the projection lamp that form no part of the claimed design.

1 Claim, 9 Drawing Sheets
